UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

BINDER.

Application filed December 20, 1922. Serial No. 607,987.

To all whom it may concern:

Be it known that I, GEORGE P. WIGGINTON, a citizen of the United States, residing at the city and county of Kalamazoo, State of Michigan, have invented certain new and useful Improvements in Binders, of which the following is a specification.

This invention relates to improvements in binders.

10 My improved binder is designed for the binding of sheets permanently and is especially designed by me for the permanent binding of sheets which have been used in loose sheet accounting, but which it is desired to preserve for permanent records. My improvements are, however, adapted for binding sheets generally.

The main objects of this invention are: First, to provide an improved binding

20 means by which sheets may be bound together so that it is impossible to separate them without substantial destruction of the binding means.

Second, to provide an improved binding 25 means for loose sheets which is simple and economical in its parts and very easily manipulated.

Objects pertaining to details and economies of the construction and operation will 30 definitely appear from the detailed description to follow.

I accomplish the objects of my invention by the devices and means described in the following specification. The invention is 35 clearly defined and pointed out in the claims.

A structure which is a preferred embodiment of the invention is clearly illustrated in the accompanying drawing forming a part of this application, in which:

40 Fig. I is a perspective view of a binder embodying the features of my invention.

Fig. II is a vertical transverse section on a line corresponding to line 2-2 of Fig. I, the post members and the clamping means 45 being shown in full lines.

Fig. III is a detail plan view of one of the sheets for which the binding means illustrated is particularly adapted.

Fig. IV is a perspective view of one of 50 the post clamping devices.

Fig. V is a plan view of a slightly modified form of the post clamping device adapted for round posts, a pair of coacting post members being shown in section.

In the drawing similar numerals of reference refer to similar parts throughout the several views.

Referring to the drawing, the sheets 1 (see Fig. III) are provided with T-shaped slots 2 adapted to receive the binding straps 60 of temporary binders. It will be understood that the shape of the holes, however, is not material.

My improved binder comprises a pair of binding bars 3 hinged to the covers 4 and 5. The binding bars are provided with post members 6 arranged in coacting pairs to slide upon each other within the sheet body as is illustrated in Fig. II; these post bars being formed to correspond with the shape 70 of the holes in the sheet. The post bars have interlocking teeth 7 on their meeting edges.

To lock the post members in clamping engagement within the sheet body I provide 75 clutch devices consisting of the bowed body member 8, which is preferably a blade spring, and a coacting pair of overlapping clamping members 9 which are secured to the outer ends of the spring body member 80 8 by means of rivets 10. The body member is provided with a slot-like hole 11 while the clamping members have slot-like holes 12 aligned therewith to receive the post members.

These clamping devices are interposed in the sheet body as shown in Fig. II and when the body member 8 is straightened, as by compressing the sheets thereon, the clamping members slide outwardly, the ends 90 of their slots engaging the post members locking them with their teeth in engagement, and when once engaged in this manner it is impossible by means of a tool or otherwise to release the clamping device or 95 disengage the post members without substantially destroying the binder.

In the modification shown in Fig. V the post members 13 are of half-round cross section, thereby adapting them to sheets having round holes therein.

My improved binding means is very simple and economical in its parts and in assembling it is only necessary to interpose the clamping members within the sheet body, 105 introduce the posts and place the binding bars carrying the posts together until the clamping devices are collapsed.

Having thus described my invention what I claim as new and desire to secure by Letters Patent is:

1. The combination in a binder for sheets 5 adapted to receive binding posts, of binding bars, binding post members mounted on said bars in coacting pairs for slidable engagement within the sheet body and having coacting interlocking teeth on their meeting edges, and a post clamping device 10 interposed in the sheet body and comprising a bowed body member and a pair of overlapping clamping members secured at their outer ends to the ends of said body 15 member, said body member and clamping members having aligned holes therein through which the post members are disposed, the clamping members being actuated to clamp said post members together with 20 their teeth in interlocking engagement when said body member is straightened within the sheet body by the pressure of the sheets thereon.

2. The combination in a binder for sheets 25 adapted to receive binding posts, of binding bars, binding post members mounted on said bars in coacting pairs for slidable engagement within the sheet body, and a post clamping device interposed in the sheet body 30 and comprising a bowed spring and a pair of overlapping clamping members secured at their outer ends to the ends of said spring, said spring and clamping members having aligned holes therein through which the post 35 members are disposed, the clamping members being actuated to clamp said post members together when the sheet body is pressed upon the spring.

3. The combination in a binder for sheets 40 adapted to receive binding posts, of coacting binding post members adapted for slidable engagement within the sheet body and having coacting interlocking teeth on their meeting edges, and a post clamping device interposed in the sheet body and comprising a 45 normally bowed body member and a pair of overlapping clamping members secured at their outer ends to the ends of said body member, said body member and plates having aligned holes therein through which the 50 post members are disposed, whereby the clamping members are actuated to clamp the post members together by the collapsing of the body member thereon.

4. The combination in a binder for sheets 55 adapted to receive binding posts, of coacting binding post members adapted for slidable engagement within the sheet body, and a post clamping device interposed in the sheet 60 body and comprising a normally bowed body member and a pair of overlapping clamping members secured at their outer ends to the ends of said body member, said body member

and plates having aligned holes therein through which the post members are disposed, whereby the clamping members are actuated to clamp the post members together by the collapsing of the body member thereon. 65

5. The combination in a binder for sheets 70 adapted to receive binding posts, of binding bars, post members arranged on said binding bars in coacting pairs for slidable engagement within the sheet body and having coacting teeth on their meeting edges, and 75 post clamping means adapted to be disposed within the sheet body and comprising a bowed body member and a pair of clamping members secured to the ends thereof and oppositely engaging the post members whereby 80 they are clamped together with their teeth in interlocking engagement when said body member is straightened within the sheet body.

6. The combination in a binder for sheets 85 adapted to receive binding posts, of binding bars, post members arranged on said binding bars in coacting pairs for slidable engagement within the sheet body, and post clamping means adapted to be disposed within the sheet body and comprising a bowed body member and a pair of clamping members secured to the ends thereof and oppositely engaging the post members whereby 90 they are clamped together when said body member is straightened within the sheet body. 95

7. The combination in a binder for sheets adapted to receive binding posts, of coacting post members adapted for slidable engagement within the sheet body and having coacting teeth on their meeting edges, and post clamping means adapted to be disposed within the sheet body and comprising a bowed body member and a pair of clamping members secured to the ends thereof and oppositely engaging the post members whereby 100 they are clamped together with their teeth in interlocking engagement when said body member is straightened within the sheet body. 105

8. The combination in a binder for sheets having holes therein adapted to receive binding posts, of coacting post members adapted for slidable engagement within the sheet body, and post clamping means adapted to be disposed within the sheet body and comprising a bowed body member and a pair of clamping members secured to the ends thereof and oppositely engaging the post members whereby 115 they are clamped together when said body member is straightened within the sheet body. 120

In witness whereof, I have hereunto set my hand and seal.

GEORGE P. WIGGINTON. [L. S.]
